(57) **CLAIM**

I claim the ornamental design for the spherical object discharging toy, as shown and described.

DESCRIPTION

FIG. 1 is a front perspective view of the spherical object discharging toy of the present application;

FIG. 2 is a rear perspective view of the spherical object discharging toy;

FIG. 3 is a front view of the spherical object discharging toy;

FIG. 4 is a rear view of the spherical object discharging toy;

FIG. 5 is a top view of the spherical object discharging toy;

FIG. 6 is a bottom view of the spherical object discharging toy;

FIG. 7 is a left side view of the spherical object discharging toy; and,

FIG. 8 is a right side view of the spherical object discharging toy.

The broken lines are for environmental purposes only and form no part of the claimed design.
